UNITED STATES PATENT OFFICE.

DAVID STEEL WALLACE, OF KOKOMO, INDIANA.

DESIGN FOR A FLUSH-TANK FOR WATER-CLOSETS.

SPECIFICATION forming part of Design No. 28,472, dated April 12, 1898.

Application filed October 4, 1897. Serial No. 654,086. Term of patent 3½ years.

To all whom it may concern:

Be it known that I, DAVID STEEL WALLACE, a citizen of the United States, residing at Kokomo, in the county of Howard and State of Indiana, have invented a new and original Design for Flush-Tanks for Water-Closets, of which the following is a specification.

This invention relates to a new and original design for a flush-tank for water-closets; and it has for its object to provide a design of this character that shall be both useful and ornamental.

The leading feature of the design resides in an approximately rectangular body having its front wall compoundly curved on sigmoidal lines to provide the same with a central convexed portion and concavities above and below the latter, which concavities merge into the convexed portion and the upper and lower edges of the body on curved lines, said body being further provided with longitudinally-concaved end walls and rounded vertical corner portions and upper and lower horizontal edge portions, which are sigmoidally curved in correspondence with the curvature of the front and end walls.

A minor feature of the design resides in the body having a straight flat back wall and a sloping bottom portion merging into a pendent tapering neck.

In the drawings, Figure 1 is a perspective view of a flush-tank for water-closets embodying the herein-described design. Fig. 2 is a vertical sectional central view thereof. Fig.

3 is a cross-sectional view on the line 3 3 of 35 Fig. 2.

Referring particularly to the drawings, the numeral 1 designates an upright body of an approximately rectangular form and having its front wall compoundly curved on sigmoidal 40 lines to provide the same with a central convexed portion 2 and concavities 3 above and below the latter, which concavities 3 merge into the convexed portion 2 and the upper and lower horizontal edges of the body on 45 curved lines.

The vertical corner portions and the upper and lower horizontal edge portions of the body are rounded and are sigmoidally curved in correspondence with the curvature of said 50 front wall, and the end walls of the body are provided with longitudinal concavities 7.

In addition to the features referred to the rectangular body 1 is provided with a straight flat back wall 4 and a sloping bottom portion 55 5, which merges into a pendent tapering neck 6 and completes the design.

What I claim is—

The design for a flush-tank for water-closets herein shown and described. 60

In testimony that I claim the foregoing as my own I have hereto affixed my signature in the presence of two witnesses.

DAVID STEEL WALLACE.
